(57) **CLAIM**

The ornamental design for an emergency warning light, as shown and described.

DESCRIPTION

FIG. 1 is a top perspective view of an emergency warning light, showing our new design;

FIG. 2 is a front side elevation view thereof;

FIG. 3 is a back side elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken lines shown are included for the purpose of illustrating portions of the emergency warning light and form no part of the claimed design.
